DANIEL BELCHER, OF ST. LOUIS, MISSOURI, ASSIGNOR TO BEMIS BRO. BAG CO., OF ST. LOUIS, MISSOURI, A CORPORATION OF MISSOURI.

METHOD OF FORMING STITCHES.

Application filed January 29, 1921. Serial No. 440,927.

This invention relates to improvements in the method of forming stitches and has for its primary object the forming of a stitch wherein a considerable amount of 5 thread is saved without sacrificing any of the strength of the stitch.

A further object is the method of forming thread saving stitches, in which intermittent tension and slack take-ups are imparted to the threads making a smooth stitch which lies close to the fabric in the finished article.

In the drawings:

Fig. 1 is a front elevation of a portion 15 of a sewing machine showing my improvements thereon.

Fig. 2 is a rear elevation of the same.

Fig. 3 is a top plan view.

Fig. 4 is a front end elevation.

Fig. 5 is a top plan view of the looper 20 thread take-up cam.

Fig. 6 is a side elevation of the same.

Fig. 7 is a top plan view of the pan tension employed on the needle bar with 25 portions thereof removed.

Fig. 8 is a vertical sectional view of the needle thread lock.

Fig. 9 is an end view of the stud on which the needle thread lock is located.

Fig. 10 is a face view of the stationary 30 cam made use of in the needle thread lock.

Fig. 11 is a face view of the movable cam made use of.

Fig. 12 is a vertical sectional view of the 35 rocking mechanism for operating the looper.

Figs. 13, 14, 15, 16, 17 and 18 are diagrammatic views showing the operation of the looper thread take-up cam.

Fig. 19 is a plan view of the looper side 40 of the stitch with a portion of the needle thread broken away and in section.

Fig. 20 is a vertical sectional view through the fabric showing the position of the needle and looper threads.

In carrying out my method I employ a 45 machine head having a base 25; secured to this base is the arm 26. The arm 26 has the bearing 27 formed integral therewith and through this bearing extends the shaft 28.

The base 25 is provided at its forward end 50 with an integral upward projection 29 in

which one end of the shaft 28 has bearing. On the other end of the shaft 28 is mounted a sheave wheel 30, and between the sheave wheel 30 and arm 26 is located an 55 eccentric 31. This eccentric may be formed integral with the wheel 30, it may be made separate and mounted on the shaft 28 or it may be formed integral with the shaft without departing from the spirit or operation 60 of my invention. Secured around the eccentric 31 is the eccentric strap 32, which has secured to and projecting from it a connecting rod 33, the free end of the rod 33 being secured to the socket 34. This socket 65 has formed on its upper end the bearing 35, which is secured to the ball joint 36. This ball joint being, in turn, secured to the projection 37 formed integral with the needle bar lever 38. The needle bar lever is piv- 70 otally secured to the arm 26 at the point indicated by the numeral 39. The end 40 of the needle bar lever is connected to the links 41, which in turn are secured to the lug 42, which lug is firmly secured to the 75 needle bar 43. Formed integral with the arm 26 are bearings 44 in which the needle bar operates. The needle bar is provided at its lower end with screw threads 45 over which the nut 46 is adapted to be secured. This 80 screw threaded portion is split and tapered, as illustrated in Fig. 1, so that the tightening of the nut 46 will securely hold the needle 47 in place. The end 48 of the needle bar lever 38 is provided with a stud 49 85 to which is secured the bearing 50, and to this bearing is secured one end of the connecting rod 51, its opposite end being secured to a similar bearing 52, which is secured to the pivot or stud 53, this stud be- 90 ing secured to the looper 54. Formed integral with the arm 26 is a projection 55 through which extends a screw threaded rod or bar 57, and on this bar are loosely mounted the pan tensions 57^a and 58,—the tension 95 57^a being for the needle thread and the tension 58 for the looper thread. The tension on these devices is regulated by means of a thumb nut 59 and coil spring 60. Extending through the projection 55 is a bar 61, 100 which is provided adjacent each end with openings. These openings serving as a guide

2

for the needle and looper thread to their respective tensions. Secured to the needle bar lever 38 is a bifurcated arm 62, which has seated in its bifurcation the arm 63 of the movable cam member 64. This cam member is provided with inclined faces 65, which contact with the inclined faces 66 of the stationary cam member 67. The movable cam member 65 is provided with a circular opening 68, which is adapted to fit over the cylindrical portion 69 of the stud 70. This stud is secured in a bracket 71, which is attached to the arm 26. The stationary cam 67 is provided with a central opening 72. This opening is square and is designed to fit over the square portion 73 of the stud 70. The stud 70 is secured in the bracket 71 by means of the nut 74 and the screw 75. My purpose in thus securing the stud is that the nut 74 will prevent longitudinal movement of the stud, while the screw 75 will prevent any turning. This turning of the stud 70 would cause a variation in the degree of tightness between the pans 76 and 77, as this degree of tightness is regulated entirely by turning the stud within the bracket 71. This turning of the stud also moves with it the stationary cam member of the thread locking device, this can be readily seen from Fig. 3. If the stud were turned so that the stationary cam member would be revolved toward the needle bar or counter-clockwise, the oscillation of the movable member would bind the pans 76 and 77 more lightly than if the stud were revolved clockwise. This binding of the pans 76 and 77 and their consequent action on the needle thread 78 is occasioned by the bifurcated bar 62 being moved up and down by the needle bar lever. This movement will in turn be communicated to the movable cam 65 and will force the stationary cam over toward the arm 26 and clamp the thread securely between the two pans. Secured to the arm 26 is a guide 79. The purpose of this is to assist in guiding the thread 78 from the pan tension 57^a to the pans 76 and 77. Secured to the needle bar lever is a loop 80. The purpose of this loop is to assist in pulling off sufficient thread for the next stitch and also assist as a pull-up for the needle thread while the stitch is being formed. Near the upper end of the needle bar 43 is placed a loop 81 through which the needle thread 78 passes. This needle thread after being passed through the loop 81 is passed through the pan tension 82. This tension is secured to the needle bar 43, and the stud 83 on which the pans 84 are secured is provided with a circular opening 85. This opening has a slot 86 extending to the outer surface of the stud 83, the purpose of this slot being to permit the ready insertion of the needle thread into the opening 85, which opening acts as

a guide for the needle thread and holds it at all times between the discs of the pan tension. The lower end of the needle thread 78 is passed through the eye of the needle 47. Secured to the upper portion of the arm 26 and extending on both sides of the needle bar 43 is a vertically adjustable U-shaped member 87 having its closed portion 88 up-turned. This member regulates the starting point of the pull up and the amount. This adjustment is accomplished by loosening the set screw 136 and raising or lowering the post 137. The loop 81 is designed to pass downward between the two parallel horizontal arms 89 of the U-shaped member 87, carrying the needle thread with it and exerting an additional pull on the thread after the same has been locked by the needle thread lock. This operation will be explained in detail later.

On the end of the shaft 28, which projects through the bearing 29, is secured a disc 90. This disc is provided with a slot 91 in which is mounted the head of a bolt 92, and on this bolt is secured one end of a link 93, its opposite end being secured in the arm 94 of the rocking frame 95. This rocking frame is provided on its lower end with bearings 96 through which a shaft 97 extends, the ends of the shaft 97 being mounted in bearings 98 formed integral with the base 25. The upper portion of the rocking frame is provided with bearings 99 in which a shaft 100 is secured and mounted on the shaft 100 is an arm 101 to which is secured the toothed feeder 102. As will be noted from Fig. 4 the link 93 is eccentrically mounted in the disc 90. This will impart a rocking motion to the frame 95. This rocking motion being in turn converted into a reciprocating motion for the feeder 102. The slot 90 is T-shaped in cross section so as to prevent the head of the bolt 92 from coming out. The head of the bolt 92 is provided with screw threads, which receive the threaded portion of the screw 103. This is for the purpose of varying the eccentricity of the link 93. This varying of eccentricity has direct bearing on the rate of feed of the fabric being sewed and consequently on the length of the stitch. Formed integral with the base 25 are vertical projecting lugs 104 and 105. These lugs are provided with a bore in which the shaft 106 is located. The shaft 106 projects through the lug 105 and has secured to its projecting end the U-shaped casting 107. This U-shaped casting is provided on its opposite end with a lug, which has bearing in the projection 29. The U-shaped casting 107 is also provided with a lug 108, which receives the screw 109, this screw acting as a pivot for the looper 54. Secured on the shaft 106 and located between the lugs 104 and 105 is a bifurcated member 110—its bifurcation straddling the cam 111, which is mounted on

the shaft 28 and rotates therewith. This cam and bifurcated member cause an oscillating motion of the looper 54; that is, causes it to rock laterally, bringing the looper first to the front and then to the rear of the needle. Formed integral with the base 25 is an upwardly projecting casting 112, to which is pivotally secured a U-shaped thread guide 113. This thread guide is also adjustable 10 up and down by means of the screw 138 which can be raised or lowered as desired, one arm of the thread guide 113 resting on the head of the screw and following it up and down. This adjustment is for the purpose of regulating the amount of slack taken 15 up and also the time at which the looper thread contacts with the looper thread take up cam. This thread guide is provided at its open end with openings through which 20 the looper thread 114 passes. This thread guide is for the purpose of directing the thread over the looper thread take up cam 115, which is mounted on the shaft 28 and rotates therewith. This looper thread cam 25 is provided with a groove 116 into which the thread remover 117 extends. This thread remover is also secured to the projection 112. Extending above the thread remover 117 is a hook 118, the purpose of which is to retain 30 the thread during a certain portion of the movement of the cam 115. The cam 115 is provided with the faces 119, 120, 121, 121^a, 122 and 123. The purposes of these faces will be explained in detail later. The projections or lugs 29 and 105 are provided on 35 their upper ends with the plane surfaces 124, and in these surfaces are formed screw threaded openings for the purpose of securing a plate thereto (not shown in the drawings), which plate acts as a rest for the work.

The base 25 is also provided with a projecting lug 125 to which a cover (not shown) is hingedly connected. This cover is for the 40 purpose of covering the mechanism, which operates the rocker frame 95. Mounted in the arm 26 is a presser foot bar 126 to which the presser foot 127 is secured and secured to the presser foot bar 126 is a projecting lug 50 128 on which one end of the presser spring 129 rests. Its other end being secured to the projecting lug 55. The desired pressure is imparted to the spring 129 by means of the adjusting screw 130. The presser foot 127 55 and bar 126 are raised by means of the eccentric lever 131. This lifting is for the purpose of making the desired adjustment of the various tensions and for threading the looper as the machine can then be easily 60 turned by hand so that the various parts assume the necessary position. The eccentric lever 131 contacts with the projecting stud 132, which is connected to the presser foot bar 126. In order to keep the bar 126 and 65 presser foot from turning I make use of the

short sliding shaft 133, which is connected to the bar 126 by means of the stud 134. This holds the presser foot in alignment with the feed plate 102 and prevents its turning when employing the eccentric lever 131.

Secured to the base 25 is a guide 135, which is for the purpose of guiding the looper thread from the pan tension to the U-shaped thread guide 113.

The operation of my device is as follows: 75

In threading the machine the needle thread 78 is first passed through the opening formed in the bar 61. This opening being on the front side of the machine. The thread is then passed underneath the bar 57 and between the pans 57^a of the pan tension, it is then passed under the thread guide 79. From there it is passed between the pans 76 and 77 of the thread lock, then through the loop 80, then upward through the loop or thread guide 81, which is attached to the upper end of the needle bar, and then downward and inserted into the pan tension carried by the needle bar. This is done by sliding one of the pans backward toward the needle bar and inserting the thread into the slot 86 and then pulling it forward until it passes into the opening 85 formed in the stud 83. The thread is then passed through the eye in the needle 47. The looper thread 114 is passed through the opening in the bar 61 on the back side of the machine, thence between the pans of the pan tension 58, then downward and through the thread guide 135. It is then passed through the openings formed in the U-shaped guide 113. This causes the thread to pass over the cam 115. The thread is then passed through the looper 54; the tension on the spring 129 is regulated, as is the tension on 90 the pans of the thread lock, and the device is ready for operation. The work is inserted beneath the front of the presser foot and then drawn beneath it by the operation of the machine. Assuming that the needle bar is raised to its highest point, as illustrated in the drawings, the sheave wheel 30 is placed in operation by means of a belt which leads from any suitable source of energy, such as a line shaft, motor, or the like. The 95 needle bar being operated by the needle bar lever 38 now commences to descend, carrying with it the needle thread 78. This operation commences to lock the thread 78 in the thread lock, while the loop 80 carries downward with it the slack, which is formed between the thread lock and the loop 81. This slack continues to form until the loop 81 is about to pass between the horizontal 100 portions of the thread take-up or U-shaped member 87. The continued downward movement of the needle bar carries this loop 81 downward still farther and exerts a downward pull on the thread. This downward pull draws up the previously formed 105 110 115 120 125 130

stitch, and also draws a certain amount of slack for the next operation or next stitch. Just as the needle is ready to descend the looper is in the position shown in Fig. 1 5 and the looper take-up cam in the position shown in Figs. 3 and 14. As the needle commences to descend, the looper thread is carried upward by the face 119 of the looper cam, as illustrated in Fig. 14, and comes in 10 contact with the thread remover 117 and rides upward thereon until it reaches the face 120 when the tension on the thread is partially removed, the thread sliding forward over the face 120 until it lodges against 15 the hook 118, where it remains until the face 121 commences to pass the hook 118 when the thread is released from the hook and allowed to drop on to the face 121. It is during this time that the needle thread 20 is pulled up taut by the needle thread slack take-up, which is composed of the U-shaped member 87 and the loop 81. This allows the needle thread to be firmly seated or drawn up tightly. At this instant the looper 25 is drawn backward to its farthest extent,—the looper then commences to travel forward and at the same time the projection 121^a of the cam 115 catches the thread and pulls it upward. This seats the looper 30 thread in the previous stitch. This pulling up continues until the thread remover 117 has carried the thread upward so that it rides on the face 122 when the thread again moves forward or is released sufficiently to 35 engage the hook 118, as in Fig. 17. The thread is now released from the hook 118 and rides on the face 123, which when pull is exerted on the thread allows it to ride downward and drop against the face 119 40 when the operation is repeated. During this movement as the needle travels upward, a loop of thread is left below the fabric and to the rear of the needle, which loop the looper enters due to its being rocked to the 45 backside of the needle by the cam 111 and the bifurcated member 110. This, as previously pointed out, oscillates the U-shaped member 107 to which the looper 54 is pivoted. The connecting rod 51 being attached 50 to the lower end of the needle bar lever 38 is pushed forward during the operation of raising the needle bar. As the needle commences to descend, the looper is oscillated forward so that it is brought to the front of 55 the needle and travels backward releasing the loop already formed with the looper thread secured therein, through which loop the needle passes. After the needle is again raised these loops are carried forward by 60 the feed plate 102 and as the needle continues to descend the loop of needle thread of the previous stitch is drawn up tight.

The saving of thread is illustrated in the following example, although any of several thread combinations may be used:

In this instance, the thread used is 5 ply for the needle thread and 3 ply for the looper thread and the basis of measurement of thread being a one ply thread so that one foot of needle thread will be equivalent to 70 5 feet of one ply thread, and one foot of looper thread equivalent to 3 feet of one ply thread. In the old stitch made by machines as used at present for bag sewing there are approximately 3.5 of 5 ply thread 75 used for every foot of sewing. This is equivalent to 17.5 feet of one ply thread, while approximately 1.5 feet of 3 ply thread is used for the same amount of sewing,—this is the equivalent of 4.5 feet of one ply thread, 80 making in all a total of 22 feet of one ply thread.

In the stitch as made by my improved method and attachments I use approximately 1.5 feet of 5 ply or 7.5 feet of one 85 ply thread in every foot of sewing, while approximately 3.5 feet of 3 ply thread are used in every foot, or 10.5 feet of one ply thread. This makes a total of 18 feet of one 90 ply thread used by my device in sewing one foot of fabric, as against 22 feet of one ply thread in the old device. This means a saving of 4 feet of one ply thread in every foot 95 of sewing, which will run into a considerable amount in the course of a day when it is figured that each machine turns out several thousand completed articles a day. As will be noted from Figs. 19 and 20, one strand of the looper thread passes entirely 100 around the loop of needle thread extending below the fabric, one strand passes through the loop and one strand is bent around one of the threads of the needle thread. This makes a total of 3 strands of looper thread 105 between adjacent loops of needle thread; and as shown in Fig. 20, by means of my improvement a portion of the looper thread is partially or wholly imbedded in the fabric depending entirely upon the coarseness 110 of weave and the material out of which the bag is formed, the thread used in sewing cement bags and the like being not as deeply imbedded as the thread used in sewing gunny sacks, the latter being made of softer and coarser material.

During the operation of my device the pan tension carried by the needle bar prevents any slack forming between it and the needle. Were this tension not present, a loop of thread would be left hanging below the needle point when the needle starts on its downward travel, and it has been found by actual experience that the needle in descending will pass through this loop of slack and cause an additional loop, which the looper will cut when entering the loop below the fabric and thus make it impossible to make a continuous stitch, there being a number of short sewed portions with open spaces left in between, which 115 120 125 130

causes the rejection of the work and consequently a loss of time and money in ripping the work and resewing it.

It will be observed from the foregoing description that the thread lock, the loop on the needle bar lever and the loop on the needle bar, the tension on the needle bar, the U-shaped member carried by the arm 26 and the looper thread take up cam co-act and are necessary in forming the stitch illustrated and described. The thread lock operates intermittently to increase the tension on the needle thread, but does not lock the thread entirely against movement. This is necessary to seat the loop of needle thread firmly around the looper thread in the formed stitch. Were this intermittent tension not present the needle thread could not be drawn up tightly by means of the U-shaped member and the loop 81. The loop 80 carried by the needle bar lever also serves the purpose of retaining the thread within the thread lock. Were this loop not present the tendency of the loop 81 would be to cause the thread to jump out of the thread lock due to the rapid up and down movement of the needle bar. The loop in the upper end of the needle bar and the U-shaped member carried by the arm 26 act as previously pointed out in drawing up the needle thread. This action taking place when the needle has almost completed its downward stroke and while the needle thread is under the additional tension imparted to it by means of the intermittent thread lock, thus taking up the slack while the needle is descending. The thread tension carried by the needle bar also performs the function of a thread support for holding the thread and preventing it from forming a double loop on both sides of the needle. In addition to the functions of the special form of looper thread take-up cam, besides forming the slack and releasing it, has another drawing-up movement, which acts as a slack take-up for the looper thread and has a tendency to cause it to lie closely to the fabric, instead of being looped between the stitches of needle thread, and it also holds the looper thread under this tension long enough to allow the needle thread to be drawn in and then it is released when the goods are being fed forward. Were this not done the looper thread would be broken.

While I have shown my attachments applied to a particular type of sewing machine, it is obvious that with slight modification they can be adapted to any sewing machine that takes thread from large spools or cones.

Having fully described my invention, what I claim is:

1. The herein-described method of forming stitches comprising the employment of a supply of needle thread and a supply of smaller

looper thread, applying to said threads near the source of supply a constant and initial tension, forming a loop in the needle thread below the fabric, passing a loop of looper thread through the needle thread loop, passing a loop of needle thread through the loop of looper thread, applying intermittent tension to the needle thread and simultaneously exerting an upward pull on the branch of the needle thread loop adjacent the intermittent tension while the same is applied, thereby drawing up and seating the first mentioned loop of needle thread against the fabric so that it extends below the fabric only sufficiently to accommodate the loops of looper thread.

2. The method of forming stitches, which consists in taking a suitable source of supply of needle and looper thread and placing the same under a constant regulated tension, drawing off a sufficient amount of thread to form a stitch, and applying intermittent additional tension and pulling up movement to the needle thread between the source of supply and the needle, and pulling up and slackening movements to the looper thread during the formation of the stitch.

3. The herein-described method of forming stitches comprising the employment of a supply of needle thread and a supply of smaller looper thread, applying to said threads near the source of supply a constant and initial tension, forming a loop in the needle thread below the fabric, passing a loop of looper thread through the needle thread loop and momentarily arresting the feed of the looper thread and taking up the slack therein while being passed through said loop, passing a loop of needle thread through the loop of looper thread, simultaneously applying intermittent tension to and exerting an upward pull on the branch of the needle thread loop adjacent the intermittent tension, thereby drawing up and seating the first mentioned loop of needle thread against the fabric.

4. The herein-described method of forming stitches comprising the employment of a supply of needle thread and a supply of smaller looper thread, applying to said threads near the source of supply a constant and initial tension, forming a loop in the needle thread below the fabric, passing a loop of looper thread through the needle thread loop, taking up and forming slack in the looper thread during different timed intervals while the stitch is being formed, passing a loop of needle thread through the loop of looper thread, applying intermittent tension to and exerting an upward pull on the branch of the needle thread loop adjacent the intermittent tension simultaneously, thereby drawing up and seating the first mentioned loop of needle thread against the fabric.

5. The herein described method of forming stitches, comprising the employment of a supply of needle thread and a supply of smaller looper thread, applying to said threads near the source of supply a constant and initial tension, forming a loop in the needle thread below the fabric, passing a loop of looper thread through the needle thread loop, passing a loop of needle thread 10 through the loop of looper thread, applying intermittent tension to the needle thread, and simultaneously exerting an upward pull on the branch of the needle thread adjacent the intermittent tension while the needle is 15 still descending and the intermittent tension still applies, thereby drawing up and seating the first mentioned loop of needle thread against the fabric so that it extends below the fabric only sufficiently to accommodate 20 the loops of looper thread.

6. The method of forming stitches which consists in taking a suitable source of supply of needle and looper thread, placing the same under a constant regulated tension, 25 drawing off more than a sufficient amount of thread to form a stitch, and applying intermittent additional tension and pulling up movement to the needle thread between the needle and source of supply during the 30 last period of the downward travel of the needle while a stitch is being formed.

7. The herein described method of forming stitches, comprising the employment of a supply of needle thread and a supply of smaller looper thread, applying to said threads near the source of supply a constant and initial tension, forming a loop in the needle thread below the fabric, passing a loop of looper thread through the needle 40 thread loop, and momentarily arresting the feed of the looper thread and taking up the slack therein, while being passed through said loop, passing a loop of needle thread through the loop of looper thread, 45 applying intermittent tension to the needle thread, and simultaneously exerting an upward pull on the branch of the needle thread adjacent the intermittent tension during the last portion of the needle descent and while the intermittent tension is 50 still applied, thereby drawing up and seating the first mentioned loop of needle thread against the fabric.

8. The herein described method of forming stitches, comprising the employment of a supply of needle thread and a supply of smaller looper thread, applying to said thread near the source of supply a constant and initial tension, forming a loop in the needle thread below the fabric, passing a loop of looper thread through the needle 60 thread loop, taking up and forming slack in the looper thread during different timed intervals while the stitch is being formed, 65 passing a loop of needle thread through the

loop of looper thread, and then applying intermittent tension to and exerting an upward pull on the branch of the needle thread thus tensioned during the last portion of the descent of the needle, thereby 70 drawing up and seating the first mentioned loop of needle thread against the fabric.

9. The method of forming stitches which consists in taking a suitable source of supply of needle and looper thread, placing the same under a constant regulated tension, 75 drawing off a sufficient amount of thread to form a stitch, applying intermittent addition tension and pulling up movement to the branch of needle thread thus tensioned 80 during a portion of the downward travel of the needle and while a stitch is being formed, and applying a constant regulated tension to the needle thread for preventing the formation of a double loop of needle 85 thread.

10. The herein described method of forming stitches comprising the employment of a supply of needle thread and a supply of smaller looper thread, applying to said 90 threads near the source of supply a constant and initial tension, forming a loop in the needle thread below the fabric, passing a loop of looper thread through the needle thread loop, passing a loop of needle thread 95 through the loop of looper thread, applying intermittent tension to the needle thread and simultaneously exerting an upward pull on the branch of the needle thread loop thus tensioned, thereby drawing up and seating the first mentioned loop of needle thread 100 against the fabric, so that it extends below the fabric only sufficiently to accommodate the loops of looper thread, and applying a constant regulated tension to the needle 105 thread to prevent the formation of a double loop of needle thread.

11. The herein described method of forming stitches comprising the employment of a supply of needle thread and a supply of smaller looper thread, applying to said 110 threads near the source of supply a constant and initial tension, forming a loop in the needle thread below the fabric, passing a loop of looper thread through the needle 115 thread loop and momentarily arresting the feed of the lower thread and taking up the slack therein while being passed through said loop, passing a loop of needle thread through the loop of looper thread, applying intermittent tension to the needle thread and simultaneously exerting an upward pull on the intermittently tensioned branch of the needle thread loop while said tension is applied, thereby drawing up and seating the 120 first mentioned loop of needle thread against the fabric, and applying a second constant regulated tension to the needle thread to prevent the formation of a double loop of 125 needle thread.

12. The herein described method of forming stitches, comprising the employment of a supply of needle thread and a supply of smaller looper thread, applying to said threads near the source of supply a constant and initial tension, forming a loop in the needle thread below the fabric, passing a loop of looper thread through the needle thread loop, and momentarily arresting the feed of the looper thread and taking up the slack therein, while being passed through said loop, passing a loop of needle thread through the loop of looper thread, applying intermittent tension to the branch of needle thread adjacent the source of supply causing the branch thus tensioned to travel in a retrograde direction while the needle is still descending thereby drawing up and seating the first mentioned loop of needle thread against the fabric, and applying a constant regulated tension to the needle thread to prevent the formation of a double loop of needle thread.

13. The method of forming stitches which consists in taking a suitable source of supply of needle and looper thread, placing the same under a constant regulated tension near the source of supply, drawing off from each a sufficient amount of thread to form a stitch, applying intermittent additional tension to one branch of the needle thread and causing a retrograde movement of the tensioned branch of needle thread, whereby the loop of needle thread is drawn up against two strands of looper thread and prevented from lying along the looper side of the fabric.

14. The herein described method of form-

ing stitches comprising the employment of a source of supply of needle thread and of looper thread, applying to said threads near the source of supply a constant and initial tension, forming a loop in the needle thread below the fabric, passing a loop of looper thread through the needle thread loop and momentarily arresting the feed of the looper thread and taking up the slack therein while being passed through said loop, passing a loop of needle thread through the loop of looper thread, applying intermittent tension to the branch of needle thread adjacent the source of supply causing the branch thus tensioned to travel in a retrograde direction while the needle is still descending thereby drawing up and seating the first mentioned loop of needle thread against two strands of looper thread thus spreading the loop of needle thread and preventing it from extending along the looper thread side of the fabric.

15. The method of forming stitches which consists in the employment of needle and looper threads, passing a loop of needle thread through the fabric to be sewed, passing a loop of looper thread through the loop of needle thread, passing a second loop of needle thread through the loop of looper thread, and imparting a retrograde movement to the needle thread through the eye of the needle, thus drawing up the first mentioned loop of needle thread tightly against two strands of looper thread.

In testimony whereof, I have signed my name to this specification.

DANIEL BELCHER.
